UNITED STATES PATENT OFFICE

CLARK F. RIGBY, OF BUTLER, PENNSYLVANIA

HEAD DEVICE FOR SAND PUMPS AND BAILERS

Application filed May 21, 1929. Serial No. 364,759.

This invention relates to a head device for sand-pumps and bailers; that is, a device which may be affixed to the upper end of a sand-pump or the like to provide means to which the sand-line or drilling cable of an oil well may be affixed.

Heretofore, it has been the practice to rivet brackets in the upper end of a sand-pump or bailer, and the drilling cable or sand-line was attached to these brackets. Due to the severe shocks and jars, which are occasioned by the operation of the pump, it has been found that the rivets invariably become loosened, and for this reason they are objectionable.

The object of the present invention is to provide means whereby a bail or U shaped member may be slidably maintained in the head or top of a sand-pump without the use of rivets.

A further object of the invention is to provide means for retaining a bail or U shaped member, as aforesaid, which may readily be removed from the sand-pump.

In the accompanying drawings Figure I is a vertical sectional view through the top portion of a pump or bailer casing, showing the device of the present invention mounted therein; Figure II is a similar sectional view taken through the same in a vertical plane at right angles to the section plane of Fig. I; Figure III is a sectional view taken in the line III—III of Fig. II; and Figure IV is a sectional view, similar to that of Fig. I, showing the device in one stage of its assembly with the U shaped bracket or bail.

The reference numeral 1 designates the pipe or casing portion of a sand-pump or bailer, which may be the inner member of a telescoping sand-pump, or the outer member thereof, when the same is to be used as a bailer, as set forth in my copending application for Letters Patent on a combination sand-pump and bailer, Serial No. 364,758, filed

May 21, 1929.

The U shaped bracket or bail 2 is the member to which the sand-line or drilling cable, not shown, is tied. Two members 3a and 3b, having grooves 4 in their faces 5 to receive

the leg portions 2a of the bail 2, are arranged

within the casing 1, as shown in Fig. I. The said casing is provided with opposed rectangular apertures 6, which correspond with the bosses 7 on the members 3a and 3b.

There is provided a central tapered member 8, which is threaded at 9 to engage the threads 10 of the said members 3a and 3b. These members are constructed with tapered annular surfaces 11, which correspond with the taper of the member 8, and obviously by screwing the member 8 down between them, these members will spread into the position of Fig. I. In this position the bosses 7 are held in the openings 6, and the assembled members are secured to the casing 1. The cap or end pieces 2b prevent the bail 2 from withdrawing from between the members 3a and 3b.

It should be noted that the bail member 2 is shown broken adjacent the top of the casing 1. This is only illustrated in this manner to keep the drawing compact; actually the bail 2 is two or three feet longer than the members 3a and 3b between which it slides. This structure has a very important utility.

It often happens that the sand-pump becomes stuck in the well casing, and when this happens, the sand-line may be slackened, which allows the bail 2 to drop into the casing, as shown in dotted lines in Fig. II. The sand-line is then hoisted, and this brings the caps 2b of the bail 2 up against the members 3a and 3b with great impact to dislodge the sticking sand-pump.

Aside from the desirability of the device, due to the ease with which it may be installed or removed, it is also greatly desirable, because it dispenses with the use of rivets or bolts. As said supra, rivets or bolts tend to become loosened. In the present arrangement no such weakness exists, because the operating strains are insufficient to shear the bosses 7 or the wall of the casing 1 into which they are secured.

It is generally desirable to attach a drilling cable or sand-line directly to the usual bottom valve operating rod of a combination sand-pump and bailer when the same is to be used as a bailer, and not as a sand-pump. Therefore, the member 8 is hollow or cored-

out to permit suitable means to pass therethrough to connect the said operating rod on said cable. This expedient will be apparent to those skilled in the art.

5 Since in the latter instance the sand-line or drilling cable is to pass downwardly to the operating rod, it is necessary to remove the bail member 2. The member 8 may be unscrewed, and the member 3 may be withdrawn from the casing 1, and the bail member removed. The elements may be then reassembled without the U member. This assembling operation is indicated in Fig. IV. First the member, say 3a, is positioned, and 10 next the member 3b is lowered until it is in the position illustrated. It will be noted that the bosses 7 are provided with threaded holes 7a. These permit the temporary insertion of bolts 12 to assist in holding the members 3a and 3b in position while the member 8 is being brought to position therebetween. After the said member 8 is tightened in position, the bolts 12 may be removed.

It will be readily understood that, due to 25 the expandable nature of the device, it may be used in various sized casings, which have but a slight difference in their diameter.

What I claim is:

1. In a device for sand-pumps and bailers 30 the combination of a casing, opposed apertures in said casing, two members having bosses thereon, a U shaped bail arranged to be held between said members, and means for separating said members to move and maintain said bosses in said apertures.

2. In a device for sand-pumps and bailers 40 the combination of a casing, opposed apertures in said casing, two members having bosses thereon, a U shaped bail arranged to be slidably maintained between said members, and means for separating said members to move and maintain said bosses in said apertures.

3. In a device for sand-pumps and bailers 45 the combination of a casing, opposed apertures in said casing, two members having bosses thereon, tapered surfaces on the members forming a tapered bore when said members are positioned opposite each other, opposed threaded regions in said members, and a member having a tapered portion and a threaded extension arranged to respectively engage said tapered bore and said threaded regions to separate said members and maintain said bosses in said apertures.

4. In a device for sand-pumps and bailers 60 the combination of a casing, opposed apertures in said casing, two members having bosses thereon, a U shaped bail arranged to be fixed between said members, tapered surfaces on the members forming a tapered bore when said members are positioned opposite each other, opposed threaded regions in said members, and a member having a tapered portion and a threaded extension arranged to

respectively engage said tapered bore and said threaded regions to separate said members and maintain said bosses in said apertures.

5. A sand pump including a cylinder with an open upper end, in combination with a device for the attachment of pump-supporting means, which device comprises a plurality of complementary blocks which are adapted to be assembled within the open terminus of said cylinder, when assembled said blocks form a bore which comprises a threaded portion and a tapering portion; and a block-separating member comprising a shank with a threaded portion and a wedge portion, said shank portions co-operating respectively with the threaded and the tapering portions of said bore for the separation of said blocks into fixed engagement with the inner wall of said cylinder.

6. The combination of the next preceding claim, together with a bail retained by said blocks in their cylinder-engaging position.

In testimony whereof I have hereunto set my hand.

CLARK F. RIGBY.
